UNITED STATES PATENT OFFICE.

GEORGE W. MOORE, OF CHICAGO, ILLINOIS.

HAIR CLIPPER.

Application filed October 28, 1922. Serial No. 597,650.

To all whom it may concern:

Be it known that I, GEORGE W. MOORE, a citizen of the United States, and a resident of the city of Chicago, county of Cook, and State of Illinois, have invented certain new and useful Improvements in Hair Clippers, of which the following is a specification.

My invention relates to improvements in hair clippers, and more particularly to the means for mounting and protecting the blades thereof, the object of the invention being to provide a simple and effective construction for this purpose.

15 Other objects will appear hereinafter.

The invention consists in the combinations and arrangements of parts hereinafter described and claimed.

The invention will be best understood by 20 reference to the accompanying drawings forming a part of this specification, and in which,

Fig. 1 is a side view, shown partially in section, of a hair clipper embodying the 25 invention;

Fig. 2, a top plan view of the same;

Fig. 3, a section taken substantially on line 3—3 of Fig. 1;

Fig. 4, a section taken substantially on 30 line 4—4 of Fig. 1; and

Fig. 5, a section taken substantially on line 5—5 of Fig. 4.

The preferred form of construction as 35 illustrated in the drawings comprises a hollow metallic handle 6 provided with a forwardly extending cutter-head 7 arranged at an angle thereto as shown. The cutter-head 7 is provided with two upstanding posts 8 and a reciprocating cutter-blade 9 is slotted 40 to fit over said posts and reciprocate in cooperating relationship with said cutter-head, suitable means being provided for effecting such reciprocation. So much of the construction constitutes no part of my 45 present invention excepting so far as same cooperates with the construction to be presently described.

A housing 10 is arranged over the blade 9 being provided at its forward edge with 50 depending lugs 11 contacting with the top of the blade to hold the same in proper cooperative relationship with the cutter-head. The lower end of handle 6 is formed into a flat guide surface substantially perpendicular to the longitudinal length of said handle. A supporting ledge or flange 12 is arranged

on the lower end of handle 6 to the rear of the blade 9 and in position to support the rear edge of the housing 10 which also rests against the lower end of said handle. The 60 housing 10 is provided with depending sides 13 and guide lugs 14 are arranged on the handle 6 to project therefrom adjacent the sides of ledge 12 to engage within and position the sides 13 which also rest against the 65 lower end of said handle. A positioning block 15 is secured centrally to the underside of the housing 10 to fit between the posts 8 to position the forward end of the 70 housing. The housing 10 fits loosely over an upstanding threaded stud 16 provided on the handle and is held in place by means of a nut 17, a spring plate or washer 18 being interposed under said nut and provided with a squared rear edge 19 resting 75 against the forward edge of the handle 6 to prevent turning.

By this arrangement a simple and effective housing is provided for holding the blade 9 in proper cooperative relationship 80 with the cutter-head 7 and also protecting the working parts from the entry of foreign matter. By means of the arrangement disclosed a strong and durable construction is 85 provided by means of which the housing will be firmly and accurately held in place.

While I have illustrated and described the preferred form of construction for carrying my invention into effect, this is 90 capable of variation and modification without departing from the spirit of the invention. I, therefore, do not wish to be limited to the precise details of construction set forth, but desire to avail myself of such variations and modifications as come with 95 in the scope of the appended claims.

Having described my invention, what I claim as new, and desire to secure by Letters Patent, is:

1. A hair clipper comprising a handle the lower end of said handle being formed into a flat guide surface substantially perpendicular thereto; a cutter head mounted on said handle; a reciprocating cutter blade cooperating therewith; a housing resting at 105 its forward edge on said blade and provided with depending sides; a supporting ledge on the lower end of said handle projecting under the rear edge of said housing, the rear edge of said housing also resting against and 110 sliding on the lower end of said handle; guide lugs on the lower end of said handle

projecting into said housing and engaging the depending sides thereof, said depending sides also resting against the end of said handle; and means for holding said housing in engagement with said plate and said supporting ledge, substantially as described.

2. A hair clipper comprising a handle the lower end of said handle being formed into a flat guide surface substantially perpendicular thereto; a cutter head on said handle; two upstanding posts on said cutter head; a reciprocatory blade slotted to fit over said posts; a housing supporting ledge on the lower end of said handle to the rear of said blade; an upstanding threaded stud located between said blade and said supporting ledge; a housing fitting loosely over said stud and resting at its forward edge on said blade, the rear edge of said housing resting on said supporting ledge and also against and sliding on the lower end of said handle, said housing being provided with depending sides resting against the lower end of said handle; guide lugs adjacent said supporting ledge and projecting from the lower end of said handle within said housing and engaging said depending sides; a spring plate fitting over said stud and resting against the top of said housing; and a nut threaded on said stud and resting against said spring plate; substantially as described.

3. A hair clipper comprising a handle the lower end of said handle being formed into a flat guide surface substantially perpendicular thereto; a cutter head on said handle; two upstanding posts on said cutter head; a reciprocatory blade slotted to fit over said posts; a housing supporting ledge on the lower end of said handle to the rear of said blade; an upstanding threaded stud located between said blade and said supporting ledge; a housing fitting loosely over said stud and resting at its forward edge on said blade, the rear edge of said housing resting on said supporting ledge and also against and sliding on the lower end of said handle, said housing being provided with depending sides resting against the lower end of said handle; guide lugs adjacent said supporting ledge and projecting from the lower end of said handle within said housing and engaging said depending sides; a spring plate fitting over said stud and resting against the top of said housing; and a nut threaded on said stud and resting against said spring plate; substantially as described.

dicular thereto; a cutter head on said handle; two upstanding posts on said cutter head; a reciprocatory blade slotted to fit over said posts; a housing supporting ledge on the lower end of said handle to the rear of said blade; an upstanding threaded stud located between said blade and said supporting ledge; a housing fitting loosely over said stud and resting at its forward edge on said blade, the rear edge of said housing resting on said supporting ledge and also against and sliding on the lower end of said handle, said housing being provided with depending sides resting against the lower end of said handle; a block on the under side of said housing between said upstanding posts on the cutter; guiding lugs adjacent said supporting ledge and projecting from the lower end of said handle into said housing and engaging the inner sides of the depending sides of the housing; a spring plate fitting over said stud and resting against the top of the housing, the rear edge of said plate being flattened and resting against the lower end of said handle; and a nut threaded on said stud and resting against said spring plate; substantially as described.

In testimony whereof I have signed my name to this specification in the presence of two subscribing witnesses.

GEORGE W. MOORE.
